Primary Examiner — Jennifer Rivard(74) *Attorney, Agent, or Firm* — John M. Lipchitz(57) **CLAIM**

The ornamental design for a shaving razor cartridge, as shown and described.

DESCRIPTION

FIG. 1 is a first perspective view of a design of a shaving razor cartridge of the present invention;

FIG. 2 is a top view thereof;

FIG. 3 is a bottom view thereof;

FIG. 4 is a left side view thereof;

FIG. 5 is a right side view thereof;

FIG. 6 is a rear view thereof;

FIG. 7 is a front view thereof; and,

FIG. 8 is a second front perspective view thereof.

The dash broken lines are directed to a handle connector and form no part of the claimed design.
